UNITED STATES PATENT OFFICE.

GEORGE W. HALL, OF ALHAMBRA, CALIFORNIA, ASSIGNOR TO COAST ENVELOPE COMPANY, OF LOS ANGELES, CALIFORNIA.

COMBINATION ENVELOPE.

Application filed August 16, 1921. Serial No. 492,712.

To all whom it may concern:

Be it known that I, GEORGE W. HALL, a citizen of the United States, residing at Alhambra, in the county of Los Angeles and State of California, have invented a new and useful Combination Envelope, of which the following is a specification.

This invention relates to devices for wrapping and covering articles to be mailed and held in a suitably packed condition.

One of the objects of this invention is to provide a case or wrapper for different qualities or varieties of mail matter to be inserted into the device through a common flap-controlled opening, the different matter being held in separate compartments.

Another object is to non-accessibly seal the compartment for the first-class mail matter, and to seal the other compartments accessibly.

Other objects will appear from the following description and appended claims as well as from the accompanying drawing, in which—

Fig. 1 is a front side view of the device.

Fig. 2 is a section on line 2—2 of Fig. 1, one flap being in open position to allow an insertion of mail matter.

Fig. 3 is a section similar to Fig. 2, having the flap closed.

Fig. 4 is a section on line 4—4 of Fig. 1.

Fig. 5 is a section similar to the illustration in Fig. 2 of a slightly modified form.

Fig. 6 is a section on line 6—6 of Fig. 1.

Fig. 7 is a fragmentary rear side view of the device, illustrating a slightly modified form of closing flap.

Fig. 8 is a fragmentary rear side view of the device, illustrating another slightly modified form of closing flap.

Fig. 9 is the whole device in form of a blank, seen from the inside, the extra pocket or compartment for first class mail being shown in proper position on the front portion of the blank.

Fig. 10 is a perspective view from the rear side of the complete device, portions of the different flaps being cut away to illustrate their relative location.

Normally it is impractical and improper to mail less than first class mail matter in the same wrapper with first class mail matter, since first class postage would be required for the whole.

By indicating on the outside that mail

matter of different kinds is placed in the wrapper, and by providing a place for attaching postage for the first class matter, devices of this type become very desirable.

A preferable form of wrapper is illustrated in Fig. 1. The whole outside cover is preferably made of one piece, a blank being illustrated in Fig. 9, having the flap 9 on the edge 10 of the main body 11, (normally called the front of a letter), a flap 12 on the edge 13, a flap 14 on the edge 15, and a flap 16 on the edge 17. The two flaps 12 and 14 are firmly connected as indicated at 18 in Figs. 4 and 10. The flap 16 is loosely and removably disposed between the front 11 and the connected flaps 12 and 14, so that this flap 16 may be withdrawn from the end indicated at 26 in Fig. 10, to allow the inspection of the matter of less than first class, normally deposited between the front 11 and the flap 16 from the end 19, indicated in Figs. 2 and 10. The flap 9 is provided with glue or similar adhesive matter along the edge indicated at 20 in Figs. 1, 2, 9 and 10. A partition 21 is secured or firmly and permanently applied to the inner surface of the front 11 along three of its edges, as indicated at 22, 23 and 24, so that the edge 25 remains free to form the opening of a smaller compartment within the larger wrapper or compartment.

First class mail matter as well as less than first class matter is in this manner to be inserted from the end 19 of the device.

After having deposited all mail matter within the wrapper from the end 19, the flap 9 is closed over the flaps 12 and 14, as illustrated in Fig. 3. The first class matter is then non-accessibly held within the device between the front 11 and the partition 21, the compartment for this matter being now firmly sealed on all four edges. Matter of less than first class, being placed between the front 11 and the flap 16, is still accessible, since the flap 16 may easily be withdrawn from the end 26, the flap 16 being loosely slipped into position as is most clearly illustrated in Figs. 2 and 4.

The indicating lettering at 27 in Fig. 1 is provided to avoid misunderstandings as to the postage, and the proper space indicated at 28 for the postage is also provided for the same reason.

At 29, an opening or a transparent portion is indicated, which is preferably at a point to

make a name or address written on an inserted letter visible and readable through the front 11 from the outside.

- 5 A slightly modified form of the device is illustrated in Fig. 5. The flap 30, extending beyond the edge 17 of the front 11, is only short (compared with the flap 16 in the illustrations 1, 2 and 3) and preferably firmly engaged and secured over the flaps 12 and 14 10 so as to permanently close that end of the device. The flap 9 in this slightly modified form is provided with a perforation 31. Clamping clips or straps, normally made of thin sheet metal, are preferably provided on 15 the outside of the connected flaps 12 and 14, as indicated at 32, to be passed through the perforation 31 in the flap 9 and spread apart as indicated at 33 in Fig. 7 for holding that end of the device closed.
- 20 A slight modification of the closing means is illustrated in Fig. 8. The flap 9 is provided with the disc 34. The connected flaps 12 and 14 are provided with the disc 35. A cord 36 is wound around the bases of the 25 discs between the disc 34 and 35 and the material of the wrapper thereby holding the flap 9 in closed relation to the whole wrapper.

I am aware that the closing means illustrated in Fig. 5, 7 and 8 are now in use, and I do not claim these parts as details of my invention, but only illustrate these means to show that my invention can be used in these modified forms.

35 Having thus described my invention, I claim:

1. In an envelope, means for separately holding mail matter of different classes, means for closing the common receiving end 40 over the whole inserted matter, and means for making matter of less than first class accessible after the closing of the common receiving end.
2. In an envelope, means for separately holding mail matter of different classes having a common receiving end, the envelope having means on the outside for distinctly indicating the position of the first class mat-

ter and for the first class postage, means for accessibly holding matter of less than 50 first class matter, and means at a separate point from the accessible end for non-accessibly holding first class matter at the common receiving end.

3. In an envelope, a main body having 55 foldable flaps on all edges, two flaps on opposite edges folded upon the main body overlapping each other and being firmly sealed together, another flap folded upon the body on the same side with the first-named 60 two flaps of a length to extend to a point near the opposite edge of the body, the second-named flap being loosely inserted between the body and the first-named flaps to terminate near the opposite edge of the body, 65 a fourth flap folded upon the body having a fourth flap folded upon the body having adhesive matter on its free edge to be sealed over the free end of the second-named flap on the outside of the first-named flaps so as to leave the second-named flap loose between 70 the body and the first-named flaps, and a partition firmly secured to the inside of the body along three of its edges having one free edge near the edge of the body along which the fourth flap is provided so as to form a 75 compartment within the space between the body and the other flaps, the open end of the last-named compartment to be sealed by the sealing of the fourth flap.

4. In an envelope having separate compartments for mail matter of different classes and having a common receiving end for the mail of different classes, means for permanently closing the common receiving end over the whole inserted matter, and 80 means for making matter of less than first class mail accessible from another end after the closing of the common receiving end.

In testimony that I claim the foregoing as my invention I have signed my name in 90 the presence of two subscribing witnesses.

GEORGE W. HALL.
